RECIPROCATING PISTON TYPE GAS
COMPRESSOR

William E. Michener, Milwaukee, Wis., assignor to Vilter Manufacturing Corporation, a corporation of Wisconsin
Filed June 23, 1961, Ser. No. 119,069
5 Claims. (Cl. 230—238)

This invention relates generally to improvements in the gas compression art, and it relates more specifically to improvements in the construction and operation of gas compressors of the reciprocating piston type.

The primary object of the present invention is to provide various improvements in the valving and control mechanism of reciprocable piston gas compressors, whereby the construction of such machines is facilitated and the efficiency is enhanced.

It has heretofore been common commercial practice to utilize compressors having several stages each embodying a cylinder and a piston cooperating with a set of annular suction and discharge valves, and provided with capacity control mechanism of opening selected suction valves in order to unload the corresponding stages.

These valves are usually formed of relatively thin but durable sheet metal and of large diameter since the suction valve of each stage or compression until ordinarily surrounds its cylinder adjacent to its outlet end and the discharge valve is located closely adjacent to but beyond this cylinder end so as to reduce the clearance space to a minimum, and each of these valves is constantly urged toward closed position by an annular series of helical compression springs. While this general type and arrangement of annular valves has long been in use, it has been difficult to properly guide the same relative to their annular inlet and discharge ports while reducing the clearance spaces to a minimum, and it was also quite tedious to apply and remove these prior valve assemblages.

Then, too, the capacity control mechanisms of these prior assemblages and which were adapted to lift the suction valves from their seats in order to unload the compressor were also relatively complicated and difficult to install; and these prior mechanisms were therefore relatively unreliable in operation and required considerable attention in order to maintain them in proper operating condition.

It is therefore an important object of the present invention to provide simple and effective means for facilitating installation of such valves and of the unloading devices associated therewith so as to insure most efficient functioning of these compressors with least attention.

Another important object of this invention is to provide far more reliable guiding of the annular plate valves of such gas compressors in order to eliminate excessive clearance space and to maintain both the inlet and discharge valves properly centralized relative to their seats and ports.

A further important object of the invention is to provide a simplified and improved capacity control device and mechanism for transmitting motion therefrom to the annular suction valve for the purpose of insuring most effective unloading of the compressor.

Still another important object of the present invention is to provide an improved valving and unloading assemblage for gas compressors, whereby various parts of these mechanisms may be readily pre-assembled and the devices may be installed as complete units within the compressor housings in proper relation to the individual cylinders.

These and other more specific objects and advantages of the invention will be apparent from the following detailed description:

2

A clear conception of the features constituting the present improvements and of the construction and operation of a typical multiple cylinder compressor embodying the invention may be had by referring to the drawings accompanying and forming a part of this specification wherein like reference characters designate the same or similar parts in the various views.

FIG. 1 is a diagrammatic side view of a multi-cylinder piston type of gas compressor embodying four pairs of radial cylinders each having therein a piston reciprocable from a common crank shaft adapted to be revolved by an electric motor;

FIG. 2 is an enlarged transverse approximately vertical section through the crankcase and through one of the cylinders and valve assemblages of a compressor such as shown in FIG. 1, with one of the capacity control units illustrated in elevation;

FIG. 3 is a further enlarged longitudinal approximately vertical but fragmentary section taken centrally through one pair of adjoining cylinders and through a portion of the corresponding capacity control mechanism, the section being taken along the line 3—3 of FIG. 1;

FIG. 4 is a slightly reduced top view of one of the improved capacity control units showing the same applied to sections through a pair of the compressor cylinders along the line 4—4 of FIG. 3;

FIG. 5 is a transverse section through the capacity control unit or unloading device of FIG. 4, taken along the line 5—5 of FIG. 6; and

FIG. 6 is an approximately vertical section through the same capacity control device, taken along the line 6—6 of FIG. 4.

While the invention has been illustrated and described herein as having been embodied in a particular type of gas compressor especially adapted for refrigeration service and embodying eight reciprocable motor driven pistons, it is not intended to necessarily confine the use of the improvements to such a compressor; and it is also contemplated that specific descriptive terms employed herein be given the broadest possible interpretation consistent with the disclosure.

Referring to FIGS. 1, 2, and 3 of the drawings, the gas compressor illustrated therein comprises in general, a main frame 9 having therein a suction chamber 10 communicating with a crankcase 10' in which a crankshaft 11 is revolvable by an electric motor 12; four pairs of cylinders 13 mounted in the frame 9 and radiating from the axis of the crankshaft 11; a piston 14 reciprocable within each of the cylinders 13 by a connecting rod 15 attached to the crankshaft 11; an annular suction valve 16 surrounding the outer end of each cylinder 13 and coacting with inlet ports 17 which are communicable with the suction chamber 10 and with the adjacent piston displacement chamber 18; an annular discharge valve 19 coacting with an annular series of outlet ports 20 which communicate with the adjacent chamber 18 of each cylinder 13 through a head 21; a cover 22 enclosing each pair of heads 21 and communicating with a common compressed gas discharge space 23; and a capacity control unit 24 cooperable with selected pairs of cylinders 13 and being operable to lift the suction valves 16 thereof in order to unload the compressor.

The main frame is preferably formed of a sturdy integral casting and when the compressor is motor driven as shown in FIG. 1, the motor 12 and frame 9 may be mounted upon a foundation base 26 as illustrated. Each cylinder 13 is provided with an integral flange 27 at its outer end in which the suction ports 17 are formed, and these cylinders and flanges are pressed into aligned bores in the frame 9 and are firmly secured therein. The annular suction and discharge valves 16, 19 are formed of thin but durable sheet metal, and each suction valve

16 is confined within a removable annular guard 28 secured to the adjacent cylinder flange 27 by cap screws 29 as in FIG. 3, and which has an annular series of small helical compression springs 30 confined therein and coacting with the adjacent plate valve 17. Each cylinder closure end head 21 is secured to another removable annular guard 31 by a bolt 32 as depicted in FIGS. 2 and 3, and each of these guards also confines an annular series of small helical compression springs 33 which coact with the adjacent plate valve 19. Each discharge valve guard 31 and cylinder head 21 is normally held within and in snug engagement with the adjacent normally stationary suction valve guard 28 by means of a large and strong helical spring 34 reacting against the adjacent cover 22; and these covers are detachably secured to the frame 9 by cap screws 35.

It is important that the periphery of each annular suction valve 16 cooperates with its guard 28 with minimum clearance and that the periphery of each annular discharge valve 19 likewise cooperates with its guard 31, in order that these valves will be constantly centralized with respect to their ports 17, 20, respectively, and the annular series of springs 30, 33 urge the valves 16, 19 toward their seats. It is also noteworthy that although the cylinder closure heads 21 are relatively thin and thus reduce the compression clearance to a minimum, these heads 21 are amply reinforced against possible distortion by the heavy guards 31 with which the heavy springs 34 coact; and the cap screws 29, 35 enable the entire suction and discharge valve assemblages to be assembled externally of the frame 9 and applied as individual units to the compressor in assembled condition or removed in like condition for inspection and possible renewal of worn or broken valves 16, 19.

The improved capacity control units 24 which coact with selected suction valves 16 for the purpose of unloading the compressor are mounted upon a partition 37 which spans the crankcase 10' but is subjected to suction pressure on both sides, as shown in FIG. 2, but each of the units 24 cooperates with both suction valves 16 of the selected pair of cylinders 13 in the manner illustrated in FIGS. 3 to 6 inclusive. Each unloading unit comprises in general a guide member 38 having thereon a central bore 39 and four upright guide pins 40 disposed parallel to this bore while two parallel upright pivot pins 41 are secured to the member 38 between the guide pins 40; a plunger 42 reciprocable within the bore 39 and having a rod 43 rising upwardly between the pivot pins 41; a horizontal H-shaped yoke 44 penetrated by and slidably along the pivot pins 41 and being constantly urged in an upward direction by relatively heavy springs 45 surrounding the shorter guide pins 40 and coacting with the member 38 and the yoke 44; a pair of levers 46 pivotally attached to the upper ends of the pins 41 by pivots 47 and coacting at their opposite ends with the plunger rod 43 and yoke 44 respectively; and means for transmitting motion of the yoke 44 to the adjacent suction valves 16 of the selected pair of compression cylinders and pistons.

Gas under pressure derived from the discharge chamber of the compressor or from any other source of control is admissible to the displacement chambers of the unloading unit plungers 42 through conduits 49, and a relatively light helical spring 50 coacts with the lower face of each plunger in order to eliminate lost motion in the leakage. The laterally projecting four prongs or arms of the H-shaped yoke 44 extend to diametrically opposed sides of the adjacent pair of cylinders 13 as shown in FIG. 4, and the free ends of these arms are adapted to coact with rings 51 which surround and are slidable along the adjacent cylinder walls and carry annular sets of parallel rods 52 reciprocable through parallel holes in the adjacent cylinder flanges 27 and which are engageable with the corresponding suction valves 16 to lift them from their seats and hold them open during unloading

operations. A helical spring 53 surrounds each rod 52 between the adjacent cylinder flange 27 and the ring 51, and each ring is recessed internally to provide a stop 54 cooperable with a snap ring 55 in order to limit the downward movement of the adjacent ring 51 as clearly shown in FIG. 3.

With the various parts of the compressor constructed as hereinabove described, the several cylinders 13 with the rings 51 and snap rings 55 applied thereto may be pressed within the radially aligned sets of openings in the frame 9 and properly positioned by means of stop rings 57 as shown in FIGS. 2 and 3, and the pistons 14, connecting rods 15, crankshaft 11 and other accessories normally confined within the crankcase 10' may be readily installed in an obvious manner upon removal of the cover plate 58. The capacity control units 24 may also be readily installed through the radial outer frame openings and applied to the cylinders 13 with which they are to cooperate, before these cylinders are installed in the frame 9.

But the suction and discharge valve assemblages including the valves 16, 19, the cylinder heads 21, the guides 28, 31, the light springs 30, 33, and the heavy springs 34 may be assembled on a workbench and applied as complete units to their respective cylinders 13 and secured in place with the aid of the cap screws 29, and the covers 22 and cap screws 35 to finish the compressor installation. These valve assemblages may also be just as readily removed for inspection and possible replacement of worn or broken valves 16, 19, with minimum effort and loss of time, and when assembled the valves 16, 19 will always be maintained properly centralized with respect to their annular ports 17, 20 by the guides 28, 31.

During normal operation of the improved compressor, the motor 12 revolves the crankshaft 11 causing it to reciprocate the several sets of pistons 14 in succession during each revolution of the cranks. During each inward travel of the pistons 14, gas will be drawn from within the suction chamber 10 through the ports 17 and past the suction valves 16 into the corresponding displacement chambers 18; and when the compressor is operating at full capacity, outward travel of each piston 14 will compress and deliver the gas admitted to its displacement chamber 18 through the ports 20 and past the discharge valve 19 into the discharge conduit 23. However, if the compressor is to be partially unloaded, the capacity control unit 24 will function to automatically hold the corresponding suction valves 16 from their seats during the discharge stroke of the adjacent pistons 14 thus preventing delivery of compressed gas from the cylinders 13 with which the units 24 cooperate.

From the foregoing description of the construction and operation of the devices, it should be apparent that the present invention in fact provides an improved reciprocating piston type of gas compressor which is simple and efficient and wherein the various parts may be readily assembled and installed or removed when necessary. The valves 16, 19 are effectively guided to prevent lateral shifting, and each cylinder has minimum clearance space thereby enhancing the efficiency of the unit, and the ports 17, 20 are usually formed as annular series of openings in a well-known manner. The improved capacity control units 24 are also compact and durable in structure and can be conveniently installed, and the entire assemblage has proven highly satisfactory and successful in commercial use especially as applied to refrigeration systems.

Various modes of carrying out the invention are contemplated as being within the scope of the following claims particularly pointing out and distinctly claiming the subject matter which is regarded as the invention.

I claim:

1. A gas compressor comprising, a main frame, a cylinder mounted in said frame and having a bore and an integral external flange at one end thereof provided with a series of suction ports, a piston reciprocable within said bore toward and away from said flanged end, an an-

nular guide ring detachably secured to said flange and forming an extension of said cylinder, said ring being provided with an annular recess facing said flange and said suction ports, the exposed inner periphery of said ring being tapered outwardly to provide a frusto-conical seat surrounding an end of said cylinder bore, an annular suction valve disposed within the recess of said guide ring and resiliently urged toward said cylinder flange to normally close said suction ports, a flat closure plate for said bore end having a tapered peripheral edge seated on the frusto-conical seat of said guide ring and having therein a series of discharge ports, an annular guide member secured to said plate remote from said cylinder bore, said guide member being formed with an annular recess facing said plate and said suction ports, an annular discharge valve disposed within the recess of said guide member and resiliently urged toward said plate to normally close said discharge ports, a cover cooperable with said frame to provide a compressed gas chamber, and resilient means interposed between said cover and said guide member to detachably maintain said guide member and said closure plate in position.

2. A gas compressor according to claim 1, wherein the resilient means between the cover and the guide member for retaining the guide member and the closure plate in position is a heavy compression spring seated at one end

on the guide member and at the other end on the cover.

3. A gas compressor according to claim 1, wherein the annular guide member is secured to the closure plate by a single central bolt and the guide ring is formed with an outwardly extending lug cooperating with the guide member to positively locate the same.

4. A gas compressor according to claim 1, wherein the main frame has complementary pairs of parallel cylinders mounted therein and each pair of complementary cylinders is enclosed by the cover.

5. A gas compressor according to claim 4, wherein the main frame is formed with aligned openings within which the cylinders are confined with the external flanges thereof snugly fitting the openings, the annular guide rings also being snugly fitted within said openings.
